UNITED STATES PATENT OFFICE.

ULYSSES S. VAUGHAN, OF LEADWOOD, MISSOURI.

STREET OR STATION INDICATOR.

Application filed February 15, 1924. Serial No. 693,065.

This invention relates to signalling devices, particularly to street indicators, and has for its object the provision of a novel device designed to be located preferably at the forward end of a street car, railway coach or the like, and provided with means whereby it may be turned step by step either automatically or by the conductor or motorman in order to display the successive stops in order that passengers may be apprised of the arrival of the car or train at the stop, street or station with accuracy instead of depending upon whatever amount of calling out the conductor may feel it incumbent upon him to do, the device consequently operating as a great convenience as will be quite obvious.

An important object is the provision of a device of this character which includes an endless belt or apron which carries the names of the streets or stations and which is moved step by step by a rotatable element under the control of the motorman or conductor, the device being furthermore so constructed that it can be operated in either direction so as to be capable of use at both ends of the car or train.

An additional object is the provision of a device of this character which will be simple and inexpensive in manufacture and installation, highly efficient in use, positive in action, durable in service, and a general improvement in the art.

With the above and other objects and advantages in view, the invention consists in the details of construction to be hereinafter more fully described and claimed, and illustrated in the accompanying drawings, in which:

Figure 1 is an elevation of the device showing it mounted within an end of a car,

Figure 2 is an enlarged elevation of my device, the full length of the endless belt or apron being displayed,

Figure 3 is a vertical sectional view taken on the line 3—3 of Figure 2,

Figure 4 is an enlarged detail view of one of the brackets which support the lower roller of the endless belt or apron structure,

Figure 5 is an enlarged view of the operating means within control of the motorman or conductor,

Figure 6 is a side elevation of the mechanism shown in Figure 5.

Referring more particularly to the drawings the letter A designates one end of a

street car, railroad coach or other similar device within which my structure is located. In carrying out my invention it is preferable to provide an elongated upright casing 60 10 which is suitably secured within the end of the car and which constitutes means for enclosing the mechanism to be hereinafter described, that is at least a portion thereof, and this casing 10 is provided with a sight 65 opening 11 through which the various station legends or indicia are adapted to be displayed. Journaled through the upper portion of this casing 10 is a transversely disposed roller 12 which projects beyond one 70 side of the casing for suitable operation and mounted within the lower end of the casing is a pair of upright brackets 13 which are formed with vertical slots 14 within which are disposed trunnions 15 provided upon the 75 ends of a lower roller 16. Trained about the rollers 12 and 16 is an endless belt or apron 17 upon which are painted or otherwise suitably inscribed the numbers or names of the 80 streets or the names of the stations as the case may be, and as indicated in the drawings. These legends are of such size as to be visible through the sight opening 11 in the casing and to be successively displayed therein as the belt or apron is moved by the 85 mechanism to be described. It should be stated that the lower roller 16 is comparatively heavy so as to hold the endless belt or apron taut at all times while at the same time not interfering with its step by step movement.

The operating means of the device comprises a preferably grooved pulley 18 which is mounted upon the projecting end of the roller 12 and about which is trained an endless belt 19 which extends over any necessary guide to a position near either the motorman or the conductor of the car. This belt is also trained about a grooved pulley 20 which is secured to a rotatably mounted 100 disk 21, both of these belts being mounted as for instance upon a stub shaft 22 or other pivotal support as indicated. Associated with this disk is a handle 23 for the purpose of effecting rotation thereof and mounted adjacent the periphery of the disk is a spring pressed pawl like member 24 which engages within successive notches 25 formed in the periphery of the disk, these notches being suitably marked so as to correspond 105 to the legends on the endless belt or apron 110 17. Owing to the provision of the marked

notches or recesses it is apparent that the motorman or conductor can tell by inspection or at a glance what street number or name is being displayed.

5 Assuming that the device has been constructed and assembled as above described, the operation is as follows: Upon reaching the successive stations or street corners, it is intended that the motorman or conductor, 10 as the case may be, grasp the handle 23 and rotate the disk 21 and of course the pulley 20 so as to impart movement to the endless belt 19 so that this movement will in turn be communicated to the upper roller 12 so 15 that rotation of the latter will be effected. As this roller 12 is turned it is apparent that the endless belt or apron 17 will be moved a step so that the next legend or street indications thereon will be exposed through 20 the opening in order that all of the occupants of the car may readily ascertain the exact street or station which they are approaching. The sole function of the pawl member 24 is to prevent the disk 21 from 25 being rotated more than a single step at a time as this pawl drops into the successive notches and constitutes a guide for effecting the exact degree of rotation of the disk to display the required legend through the opening 11. When the car has reached the 30 end of the line and is started back on its return trip it is of course apparent that there is nothing at all to interfere with rotating the disk 21 in the reverse direction 35 as the pawl 24 does not have a ratchet action but is simply a movable detent for making sure that the disk will be moved only one step.

From the foregoing description and a 40 study of the drawings, it will be apparent that I have thus provided a very simple and consequently inexpensively constructed station indicator which will be highly advantageous for use especially as it will prevent a passenger from unknowingly passing 45 his station or street. The device also renders it unnecessary for the conductor to call out the names of the streets or stations and this is also a distinct advantage especially

in view of the fact that such calling out is 50 so confused and frequently so mumbled that passengers cannot understand what is being said. Owing to the simplicity of the construction and the fewness of the parts it is apparent that there is nothing to get out 55 of order and that the device should consequently have a long life and satisfactorily perform all the functions for which it is intended.

While I have shown and described the 60 preferred embodiment of the invention, it is of course to be understood that I reserve the right to make such changes in the form, construction and arrangement of parts as will not depart from the spirit of the invention or the scope of the subjoined claim.

Having thus described my invention I claim:

A station indicator comprising an elongated upright casing designed to be mounted 70 within the end of a car and formed with a sight opening, an upper roller journaled within said casing and extending transversely thereof, a lower roller vertically movably mounted and also journaled 75 within the lower portion of the casing, an endless apron trained about both of said rollers and bearing a series of names of streets or stations successively capable of being displayed through said sight opening, 80 a pulley secured upon the projecting end of said first named roller, a pulley journaled within reach of the car attendant, an endless belt trained about both of said pulleys, 85 a disk carried by said second named pulley, provided with indications corresponding to the successive legends on the endless apron, a handle for turning said disk, said disk having 90 its periphery formed with a plurality of notches located opposite the indicia thereon, and a detent movably mounted and engaging within said notches whereby to insure step by step movement of the disk and consequently the apron.

In testimony whereof I affix my signature.

ULYSSES S. VAUGHAN.
